UNITED STATES PATENT OFFICE.

JOSEPH F. DWYER, OF SEATTLE, WASHINGTON.

DESIGN FOR A CASING FOR A TICKET-DISPENSING MACHINE.

53,678.

Specification for Design.

Patented Aug. 5, 1919.

Application filed March 24, 1919. Serial No. 284,883. Term of patent 14 years.

To all whom it may concern:

Be it known that I, JOSEPH F. DWYER, a citizen of the United States, whose post-office address is Pacific Block, in the city of Seattle, county of King, and State of Washington, have invented a new, original, and ornamental Design for a Casing for a Ticket-Dispensing Machine, of which the following is a specification, reference being had to the accompanying drawing, forming a part thereof.

The figure is a perspective view of a ticket dispensing machine adapted to hold and dispense tickets, showing my new design.

I claim:

The ornamental design for a casing for a ticket dispensing machine as shown.

JOSEPH F. DWYER.
